Attorney

UNITED STATES PATENT OFFICE.

JOSEPH A. GOYETTE, OF PROVIDENCE, RHODE ISLAND.

DESIGN FOR A TOWER-BELL ENGAGEMENT-RING.

59,838.

Specification for Design.

Patented Nov. 29, 1921.

Application filed August 31, 1921. Serial No. 497,388. Term of patent 7 years.

To all whom it may concern:

Be it known that I, JOSEPH A. GOYETTE, a citizen of the United States, residing at Providence, in the county of Providence and State of Rhode Island, have invented a new, original, and ornamental Design for a Tower-Bell Engagement-Ring, of which the following is a specification, reference being had to the accompanying drawing, forming part thereof.

Figure 1 is a side view of the ring embodying my design,

Fig. 2 is an edge elevation thereof.

Fig. 3 is a top plan view thereof, and

I claim:—

The ornamental design for a tower bell engagement ring as shown.

JOSEPH A. GOYETTE.
